(57) **CLAIM**

The ornamental design for an automatic swimming pool cleaner as shown and described.

DESCRIPTION

1. Automatic swimming pool cleaner

1.1 : Front

1.2 : Back

1.3 : Left

1.4 : Right

1.5 : Bottom

1.6 : Top

1.7 : Perspective

1.8 : Perspective

1.9 : Perspective

1.10 : Enlarged view of portion 10

Protection is not sought for the matter shown by means of
dotted lines or broken lines in the reproductions.

1 Claim, 10 Drawing Sheets
